E10.6.

FIG. 7.

FIG. 1 is a side perspective view of an airplane embodying our new design and illustrating the airplane in flight;

FIGS. 2 and 3 are side and front elevations, respectively, of the airplane;

FIGS. 4 and 5 are top and bottom plan views, respectively, thereof;

FIG. 6 is a side elevation of the airplane with the rotatable ducted propellers in position for vertical propulsion; and

FIG. 7 is an enlarged perspective view illustrating the rear of the fuselage in detail.

The side of the airplane not shown is a mirror image of the side shown.

We claim:

The ornamental design for an airplane, substantially as shown and described.
